UNITED STATES PATENT OFFICE.

HERMAN BESSER AND JESSE H. BESSER, OF ALPENA, MICHIGAN.

MOLD BOX.

Application filed May 12, 1923. Serial No. 638,602.

To all whom it may concern:

Be it known that we, HERMAN BESSER and JESSE H. BESSER, residents of the city of Alpena, in the county of Alpena and State 5 of Michigan, and citizens of the United States of America, have invented certain new and useful Improvements in Mold Boxes, of which the following is a specification.

10 Our invention relates to new and improved molds for molding blocks or other cement or concrete products for building or other purposes of solid or hollow form, and of rectangular or other quadrilateral shape 15 in general, one that may be locked in closed relation for receiving the cement material and which may be readily and quickly released without injuring the product, leaving the sides, ends and corners perfect, and one 20 which will furnish a perfectly "squared" opening in the mold when its parts are closed and the nature of its construction tends to positively keep the same in proper adjustment.

25 It is a special object of our invention to provide a mold box that shall comprise sides and ends, the former pivoted to a common framework at the rear of the end plate, and also having the front end plate pivoted to 30 a side plate appreciably back of the front end of the same, for a purpose to be fully explained.

35 It is a further object of our invention to provide a mold box in which the front end plate serves further as a lock element for the sides of the mold, and also as a means for manually lifting the side to which it is pivoted; and in which the latch member is carried by the other side plate and also 40 serves as the means for lifting that side, so that the locking elements for the device provide manual means for lifting readily the entire front end of the mold after the side plates have been separated.

45 It is also an object of our new construction to provide especially strong side plates without using truss elements, and without adding strengthening members that will be cumbersome in themselves or in combination 50 with the plates with which they are used, in fact, the strengthening bars we use for these side plates serve an additional purpose other than that of making the plates more rigid, as will appear from our description now to 55 be given.

It is a further object to provide the side

plates of our new mold of greater width than the end plates so that they may serve as a hopper to properly direct the material into the mold when the parts are closed, the 60 edges of these plates forming a gage for directing the movement of the "strike-off" tool, though the latter is so constructed that it trowels off the material at the level of the 65 end plates.

Further objects and advantages will appear in the following description, it being understood that various changes in form and minor details of construction may be resorted to within the scope of the appended claims. 70

We attain these objects in the following manner, reference being made to the accompanying drawings, in which:—

Figure 1 is a perspective view of our mold box; 75

Figure 2 is a plan view of the same with the parts swung open;

Figure 3 is a perspective of the pivoted end gate in its closed relation with the side plate, the latch being unlatched, and 80

Figure 4 is a perspective of the end gate shown pivoted to the front portion of one of the side plates.

Referring now to the drawings in detail, our mold box comprises two side plates A and B, a rear end plate C and the front plate D, the latter part forming an integral portion of the locking mechanism for the entire unit, as will be later explained. The side plates have fixed to their lateral edges flanged bars 10, L-shaped in cross section, the vertical flanges being riveted to the plates so that the horizontal flanges are flush with the edges of the plates, these bars 10 serving to positively strengthen the plates A and B, to afford horizontal flange strips for attachment of other members, and when extended rearwardly beyond the end plate C, as later explained, affording pivot points at very advantageous distances from the plate C. Bars 10 are extended at 11 and pivoted at 12 to a cross bar 13, while the corresponding lower bars 14 are extended rearwardly and pivoted at 12 to the cross bar 15 which is of the same length as 13, both being preferably formed of L strips for great strength and ease in attaching other elements. 100

Extending forward from the cross bars 13 and 15, are narrow frame plates 16 and 20 whose forward ends enter the space between the side plates somewhat forward of their rear ends. The upper plate 16 is riveted, or 105 110

otherwise secured to the bar 13 at a plurality of points 17, is downwardly offset at 18 and is provided with a downwardly turned lip which is similarly fixed to the upper edge of the plate C, as at 19. The lower plate 20 is secured to 15 at 21 and directly fastened to the lower edge of the end plate C. It will thus be understood that the parts 13, 15, 16, C and 20 form a rigid frame part upon which the side plates A and B are fulcrumed.

The up-turned lip 22 of the lower bar 15 has integral therewith ends bent rearwardly to form ears or lugs 23 to afford suitable pivot points for a roller 24 upon which the entire mold may be wheeled as a unit, when it is desired to so support it.

The front end plate D is long enough to lap beyond the ends of the side members, when the latter are in closed position, and is mounted upon a plurality of L-bars 25 and 26, the latter being the longer. One arm of bar 26 is riveted to the plate D near its lower edge, and 25 is similarly secured somewhat below the upper edge, a spacer bar 27 being secured near the angle of the bars 25 and 26 and within the edge of the plate D, so that when the parts are closed, the pivot ends of these bars will be parallel with the side B. These rear ends of the L bars are pivoted to the side plate B by swinging attachment to the flange 14 and to a lug part 30 riveted to the side plate. A handle 28 is secured to said plate as by rivets 29, the latter extending through plate 33 and spacer whereby parts 27, 28 and D are fixed together.

It is to be noted that the plate D is narrower at the top than at the bottom. The wider edge permits an upwardly directed tongue 31 to be spaced from the main portion of the plate, thus forming a locking slot 32 for receiving therein a lever 33 pivoted at its rear end upon the side plate A having a slot 34 on its lower edge for engaging the bottom edge of the slot 32 whereby lever 33, when locked, holds gate D from opening outward and itself prevented from being wrenching off from A by engagement with tongue 31. A small latch 35 pivoted on the outer face of A swings on a horizontal fulcrum to lock 33 in its engaged relation with 32. A handle 36 on 35 provides convenient means for manipulation of the latch.

Since plate D is hinged quite securely to B and is provided with handle 28; and since lever 33 is hinged securely to A and further provided with a handle part 37, it results that, when the parts are unlatched, the parts 28 and 37 may be grasped by the hands of the operative to lift the front part of the entire mold device while the rear part rests upon the roller 24. The entire mold can therefore very conveniently be wheeled away from the previously molded block like

a barrow, leaving the molded block in position on the floor, or pallet upon which the block is formed. The outlines of the formed block are shown in Fig. 2 in dotted lines.

When it is desired to form grooved creases in the sides of the block, narrow metal strips 38 are fixed upon the inner faces of the plates A and B, which strips may be positioned horizontally or vertically, and may be one or more in number, or may be provided in intersecting relation; though they may also be used upon the end plates C and D as well, if the same resulting effect be sought upon the ends of the block, as will be evident.

In operation, the mold parts are placed in vertical position on some smooth support, the side plates swung into closed relation by manipulating the handles 28 and 37, the lever 33 swung down into the notch 32 and the latch lever 35 swung into locked position above the lever 33. The mold is now ready for the reception of the concrete or other molding material, the raised sides of the plates A and B affording a hopper for directing the material into the mold space bounded by A, B, C, and D. The material having been packed down in any manner, such as by tamping, the top of the mold is now smoothed off or troweled, as by a "strike-off" comprising end portions resting upon the edges 10 and a portion extending down to the level of the upper edges of the ends C and D, thereby resulting in a block having the exact height of the end plates. The latch 35 is now unlatched, the part 37 raised, when parts A, B and D will spring outward automatically releasing the molded block at substantially all points. The mold can now be wholly removed by grasping handles 28 and 37, exerting a tendency at first to further separate the side plates, then lifting them somewhat, and finally pushing forward to remove the entire mechanism to a new position where the operation may be repeated.

Our mechanism is by no means limited to molding blocks that are solid, it may be used in forming hollow products as well, and so used without modifying the mechanism thus far described. If hollow spaces are desired in the finished blocks, it is only necessary to insert one or more cores in the mold in the position desired for production of the hollow block, and the remainder of the operation will vary in no way from that recited above. To hold these cores in suitable position, corresponding openings are or may be made in the mold plates for receiving them while the tamping operation is being performed, after which they may be removed. In Fig. 1 is shown dotted line formation on plate B of the shape of two openings such as may be used for guiding

cores in the closed position of the mold, if hollow blocks are to be molded. These cores and openings may be in any plane and in the number desired, no further explanation of their operation being thought essential for their use.

While our mold has side plates with V-shaped strips on their inner faces, we are by no means to be limited to projections of such shape. The inside of the mold can well be provided with projections of different sizes and shapes so that concrete products can be molded having corresponding indentations for ornamental or for other purposes. Also, though we have shown our mold having end gates lower than the side plates, the mold can of course be made with the four exterior plates of the same height.

Having described our invention in its structure and in certain of its applications, what we claim and desire to protect by Letters Patent is:—

1. A mold comprising side and end plates, the rear end plate being mounted within the sides and the front plate overlapping the ends of the side plates and pivoted to one of them.

2. A mold comprising side and end plates, means for supporting the rear end plate in relation to the sides, and angle bars having one arm of each fixed to the front end plate and the other arm pivoted to the exterior face of one of the sides.

3. A mold comprising side and end plates, a common framework upon which the rear end plate is mounted and to which the side plates are pivoted, the front end plate overlapping the ends of the side plates, and means for pivoting the said front end plate to one of said sides remote from its front end.

4. A mold comprising side and end plates, the front end plate overlapping the ends of the sides and pivoted to one of said sides, a rigid framework extending rearwardly beyond said sides and the rear end plate being fixedly mounted thereupon and the said side plates pivoted thereto.

5. A rectangular mold comprising front and rear end plates, a fixed frame structure for holding the rear end plate in molding position, cross bars secured to said frame structure, side plates, reinforcing bars fixed to the side plates and extending rearwardly from the latter and pivoted to the ends of the cross bars.

6. A concrete mold comprising side and end plates, a supporting frame for the rear end plate, including longitudinal plates secured to the rear end plate and transverse bars fixed to said longitudinal plates, the side plates having rear extensions pivoted to said transverse bars, and pivoting means for the front end plate comprising, angle bars each having one arm pivoted to the exterior

face of one of the side plates remote from its front edge, and the other arm directly secured to said front end plate.

7. A concrete mold comprising side and end plates, spaced longitudinal plates fixed at their forward ends to the rear end plate of the mold, cross bars fixed to the rear ends of the said longitudinal plates, and flanged reinforcing bars secured to the lower edges of said side plates and extending rearwardly from the ends of the latter and pivoted at their ends to the ends of said cross bars.

8. In a mold the combination of parallel side plates and a front end plate pivoted to one of them, a rear end plate within the mold and abutting the inner faces of the side plates, longitudinal frame plates fixed to the upper and lower ends of the rear end plate, cross bars secured to the rear ends of the said frame plates respectively, and means secured to the side plates for pivotally mounting the latter upon the ends of such cross bars.

9. A concrete mold comprising relatively high side plates, a lower rear end plate fixed in position inside the side plates, and a low front end plate overlapping the ends of said sides and pivoted to one of them.

10. In a mold comprising side and end plates, reinforcing members fixed to said side plates and pivoted rearwardly thereof, in combination with a front end plate having angular supporting members fixed thereupon and pivoted to the exterior face of one of the sides.

11. In a rectangular mold, an overlapping end plate in combination with means for pivoting the same upon the exterior face of one of the side plates, comprising angle bars having cross arms secured to the end plate, and longitudinal arms pivoted at their ends to the said exterior face and parallel to the side plate when the mold is closed.

12. A mold having side and end plates, one of the end plates fitting within the side plates at their rear ends, and the other end plate mounted at the front ends of said side plates, means for pivoting the front end plate to the exterior face of one of the side plates remote from the end of the latter, a handle secured to said front end plate and pivoting means, and a handle pivoted to the other side plate.

13. In a concrete mold having side and end plates, one end plate mounted fixedly within the side plates, the other end plate overlapping the front ends of the side plates and serving as an end gate and having thereon a handle member, and another handle member pivoted to the other side plate and serving as a latch for the front end gate when the mold is closed.

14. A concrete mold having side and end plates, reinforcing extensions fixed at their forward ends to the side plates, and a pair

- thereof extended to the rear and mounting a roller in their ends, a front end plate pivoted to one of said side plates, a handle lever pivoted on the other side plate, and a handle member fixed on said front end plate, whereby the operator may grasp the two handle members and lift the front end of the mold.
15. In a concrete mold having four plates adapted to be connected to form a rectangular interior, a front end gate overlapping the ends of the side plates and having means for pivoting the same upon the exterior face of one of the said sides said front end plate having a notch in the overlapping edge remote from its pivot and a pivoted latch lever mounted upon the exterior face of the other side plate and having on its lower edge a notch adapted to register with the end plate notch when the mold is closed.
16. A mold comprising side and end plates, the front end over-lapping the ends of the side plates and pivoted to one of them remote from its front end.
- 25 17. In a rectangular mold, an over-lapping end plate in combination with means for pivoting the same upon the exterior face of one of the side plates, comprising angle bars secured to the end plate and pivoted to said exterior face remote from the end of the side plate.
- 35 18. In a concrete mold having side and end plates, the front end plate over-lapping the ends of the side plates, and having thereon a handle member, and another handle member pivoted to one of the side plates, and serving as a latch for the front end plate when the mold is closed, and the two handles serving for manually lifting the front end of the mold.
- 45 19. A concrete mold comprising relatively high side plates, a low front end plate pivoted to one of the sides, a lower rear end plate mounted within the sides, and means for mounting the latter comprising a pair of transverse bars spaced apart vertically the height of the said side plates, longitudinal plates secured at their rear ends to the said bars respectively, the front end of the lower plate being bent up for securing to the upper edge of said end plate, and the upper of said longitudinal plates being bent downward to the level of the upper edge of the end plate and secured thereto.
20. A mold comprising side and end plates, the rear end plate being mounted within the side and the front plate pivoted to one of them remote from its front end.
21. In a mold comprising side and end plates, reinforcing members fixed to said side plates and pivoted rearwardly thereof, in combination with a front end plate pivoted to the exterior face of one of the sides.
22. A mold comprising side and end plates, means for supporting the rear end plate in vertical position within the sides, and reinforcing members fixed to said side plates and pivoted rearwardly to said supporting means.
23. In a mold box comprising side and end plates, a supporting stationary frame structure for holding the rear end plate in molding position within the sides, comprising parallel, transverse rigid bars mounted in parallelism in spaced relation, one above the other, and a pair of spaced longitudinal plates, each of which has its rear end fixed to a corresponding transverse bar and its forward end bent vertically and secured to said end plate.
24. A mold comprising side and end plates, means for mounting the rear end plate within the sides, said means extending rearwardly of the latter and including vertically spaced, transverse bars, and a pair of reinforcing members fixed to each of said side plates adjacent the upper and lower edges thereof, respectively, and rear ends of said reinforcing members being pivoted to the ends of said transverse bars.

In testimony whereof we hereunto affix our signatures.

HERMAN BESSER.
JESSE H. BESSER.
